DESIGN FOR A PITCHER OR SIMILAR ARTICLE

Walter Karl Titze, Oklahoma City, Okla., assignor to Universal Potteries, Inc., Cambridge, Ohio, a corporation of Ohio

Application July 1, 1938, Serial No. 78,214

Term of patent 3½ years

To all whom it may concern:

Be it known that I, Walter Karl Titze, a citizen of the United States and a resident of Oklahoma City, county of Oklahoma and State of Oklahoma, have invented a new, original, and ornamental Design for a Pitcher or Similar Article, of which the following is a specification, reference being had to the accompanying drawing, forming a part thereof.

In the drawing:—

Fig. 1 is a side elevational view of a pitcher or similar article showing my new design; Fig. 2 is a side elevational view taken on the handle side of the pitcher; Fig. 3 is a side elevational view taken upon the spout side of the pitcher; Fig. 4 is a top plan view of the pitcher.

I claim:

The ornamental design for a pitcher or similar article, as shown.

WALTER KARL TITZE.
